CONTACT LENS CASE

Robert E. Middleton, Englewood, and Gary L. Switser, Boulder, Colo., assignors to R & F Products, Inc., Englewood, Colo.

Filed July 30, 1971, Ser. No. 167,887

Term of patent 14 years

Int. Cl. D16—06
U.S. Cl. D57—1 B

FIG. 1 is a perspective view of the contact lens case showing our new design;

FIG. 2 is a perspective view thereof with the left lens pocket in an open position;

FIG. 3 is a perspective view thereof with the right lens pocket in an open position;

FIG. 4 is a top plan view thereof;

FIG. 5 is a bottom plan view thereof;

FIG. 6 is a side view thereof;

FIG. 7 is a top plan view thereof with the lens pocket moved to the left;

FIG. 8 is a top plan view thereof with the lens pockets moved to the right;

FIG. 9 is a bottom plan view of the case as it appears in FIG. 7; and

FIG. 10 is a bottom plan view of the case as it appears in FIG. 8.

We claim:

The ornamental design for a contact lens case, as shown and described.
